APPARATUS FOR COOLING MOLDS

Colin C. Cowgill, Gary, Ind., assignor to United States Steel Corporation, a corporation of New Jersey
Filed June 17, 1965, Ser. No. 464,790
4 Claims. (Cl. 164—154)

This invention relates to a method and apparatus for cooling hot molds. More particularly, the invention relates to a method and apparatus for cooling hot molds with minimum damage to the molds themselves and to provide molds in a condition to be quickly re-used. Still more particularly, the invention is useful in automatically cooling hot molds which have been used in casting steel ingots.

Prior to the present invention, hot molds were cooled by manually activated cooling systems, usually comprising a number of water sprays positioned to supply water to the mold surface. Since such systems required manual operation, they were not well controlled. The mold temperature at the start of cooling was generally unknown, and as a result, cooling of the molds often began either when the molds were too hot, causing serious damage to the molds, or too cold, causing waste of time and facilities. More importantly, poor cooling of the molds results in unsatisfactory ingot quality because the molds were frequently cooled to too low a temperature for casting. In addition, a safety hazard is presented when water remains in the mold at pouring time due to unnecessarily long cooling cycles or because the molds are cooled down too far to vaporize residual water. As a result, pouring hot metal into cold or wet molds causes poor ingot surface quality due to excessive spitting and splashing during metal pouring, and often uncontrollable de-oxidation practices, particularly on mechanically capped and semi-killed steels. Thus, manual systems have not proven satisfactory because of the lack of control.

The present invention provides an improved automatic system for cooling hot molds which is easily used and simply constructed. According to the invention, a system is provided for cooling hot molds which comprises an infrared sensing device adapted to sense radiant energy emitted from a plurality of hot molds and a cooling system for spraying liquid coolant on the hot molds in response to the radiant energy level sensed by the infrared sensing device.

An apparatus or system according to the invention is described in the accompanying schematic drawing which shows a plurality of hot ingot molds 10 which are transported in ingot buggies 12 into the ingot cooling area on track 14. An infrared sensing device 20 is positioned to sense and measure radiant energy emitted from a plurality of ingot molds and transforms the radiant energy sensed into an electrical signal which is transmitted to an amplifier 30. The amplifier demodulates and filters the signal and amplifies it to correct amplitudes to provide a suitable voltage to temperature recorder and controller 40. Controller 40 activates the cooling system by energizing a spray timer 50 and a spray relay 60. The spray relay 60 operates a spray solenoid 70 that controls main valve 72 which supplies coolant from a cooling source through a suitable fluid line 80 to a header 82 and through spray lines 84 to individual sprays 86.

It has been determined that in cooling iron molds which have been used in casting steel ingots, the coolant, e.g. water, should not be applied to the hot molds until the molds are below about 1100° F. or else mold life is significantly shortened. The full explanation is not entirely clear; however, it is believed that cooling from much above about 1100° F. alters the metallurgical structure of the molds sufficiently to impair the usefulness of the mold by reducing its potential life. For this reason, in the preferred embodiment of the invention, coolant is not

applied to the molds until the mold temperature is indicated to be below about 1100° F.

Similarly, it has been found that for optimum casting practice the molds supplied therefor should not be cooled to below about 550° F. If the molds are cooled much below this temperature, the tendency for residual water to remain in the molds and interfere with metal casting increases considerably. Moreover, as discussed above, unnecessary cooling ties up mold cooling equipment thereby wasting time and mold cooling facilities.

It is particularly desirable to cool the hot molds in steps rather than to continuously cool to the desired low temperature. Intermittent coolant permits the mold temperature to equalize and minimizes the development of thermal stresses in the molds which shorten mold life by increasing the incidence of mold damage. To accomplish intermittent cooling, the system is adjusted so that while the cooling system is activated, a cooling cycle is used which includes "spray-on" and "spray-off" periods in a regular sequence until the mold temperature, as indicated by the infrared detector, is below about 550° F. which is the temperature found to be the desired minimum to which iron molds should be cooled for optimum steel casting practice.

The arrangement described in the drawing illustrates how commercially available items can be combined into a new automatic cooling system which provides the aforementioned advantages. Although many temperature indicators are available, it has been found that a narrow band infrared radiant energy receiver is essential in the system for the necessary accuracy over the temperature range encountered and in the environment involved. The infrared receiver used must be capable of measuring radiant energy with wave lengths of from 1 to 7 microns, preferably 2.0 to 2.6 microns, within the target area of the detector. The infrared sensing device is aimed so that its target area includes a plurality of molds and the reading given by the device will more accurately reflect the temperature of the group of molds involved rather than the merely local temperature of a small area of mold surface. The objective lens are removed from the infrared device in order to increase the field area. For optimum use, the infrared sensing device is aimed so the centerline of the sensing field strikes the line of molds at an angle of $\pm 15^\circ$ ($\pm 75^\circ$ from the perpendicular). This orientation provides a much larger target area than when placed at a 90° angle, but does not change the total radiant energy detected. The amount of flux density (radiant power) detected remains the same, for any given temperature, regardless of the angle of incidence because the instrument "sees" a spot rather than a point, and an increase in area resolved compensates for a decrease in radiant energy (which varies as the cosine of the angle between the normal and the particular direction—by Lambert's Law). At an angle of 15° a "missing" mold in the line will not significantly affect the total radiant energy from the target, since the end wall of the next mold will find the void in the target. The target area is large enough to initiate a response which is proportional to the average mold temperature and it provides dependable operation. Average mold temperature may be assumed to be represented by a point at the center of the surface of the mold sidewall which is 24 inches up from the bottom of the mold, and temperatures measured at this point can be used as a control check on temperatures obtained by the infrared units. Compensating adjustments in the output of the infrared device can be made via the emittance control on the amplifier. The sensing head may best be aimed by temporary installation of the standard objective lens and sighting through the telescopic optical system to locate the center of the target. A locking type swivel base may be provided to facilitate aiming the sensing device.

In operation, the infrared detector 20 indicates the mold temperature by automatically sensing the radiant energy emitted from the molds and translates the radiant energy sensed into a proportional electrical output. The signal voltage from the infrared sensing unit is transmitted to an amplifier 30 where the signal is demodulated, filtered and reduced to correct amplitudes to drive an amplifier meter and to provide a suitable voltage input to external temperature recorder and controller 40. A suitable sensing device for use according to the invention is an Ircon Infrared Thermometer, Model 300T-2 (which includes both a radiation sensing-head 20 and amplifier 30) manufactured by Ircon, Inc., Chicago, Illinois. A suitable recorder-controller is Minneapolis-Honeywell circular chart electronic recorder Model No. 152X-13-RA-Q3-II-W5-11-A4. Within the recorder are a normally-open low temperature contact 42 and a normally-closed high temperature contact 44. The low temperature contact 42 closes at approximately 550° F. and the normally-closed high temperature contact 44 opens at approximately 1100° F. These contacts automatically energize a repeat cycle spray timer 50 whenever the mold temperature corresponding to the radiant energy as measured by the sensing device 20 is between about 550° F. and 1100° F. A suitable repeat cycle timer is the "Flexopulse Repeat Cycle Timer" No. HG84A6, manufactured by Eagle Signal Co., and described in company bulletin No. 320.

The switching action of the timer 50 is used to energize and de-energize spray relay 60 which, in turn, energizes and de-energizes spray solenoid 70 which controls a double acting main water valve 72. The timer runs continuously, when energized, until power is interrupted by excursions beyond the hi-low limits of the recorder-controller. The timer contains an indicator which oscillates continuously between the settings of two adjustable stops, and trips a single-pole double-throw switch at midpoint, thereby controlling "on" and "off" periods of the cooling cycle. The adjustable stops can be set to provide "on" or "off" period of 5 seconds through 20 minutes. The presently preferred conditions include periods of 5 minutes "on" and 3 minutes "off." The timer's double-throw switch contains contact points 1, 2 and 3 as shown in the drawing. The 3-2 contact in the timer energizes the spray relay 60 which activates the spray solenoid 70 and valve 72. After the timer completes its "spray-on" cycle, the 3-2 contact opens thereby de-energizing the spray relay and shutting off spray solenoid 70 (closing valve 72). The 2-1 contact closes as the 3-2 contact opens and the timer continues through the "spray-off" period, then repeats the "spray-on" cycle. When de-energized by the recorder controller, the timer always stops at the end of an "on" period with the 2-1 contacts closed as a result of a normally-open contact 62 in the spray relay 60 which "seals-in" the circuit during the "spray-on" period of the cycle so that the timer will go through a complete pre-set "on" cycle once energized. The "seal-in" function of contact 62 serves to overcome erratic operation that might result from the effect on the sensing unit of occasional excesses of water and steam in the cooling area. When the temperature of the molds is brought below 550° F., the timer is de-energized by the recorder-controller contact 42 and the 2-1 contacts will remain closed at the end of the "on" period.

As can be seen, the timer always starts at the beginning of an "off" period which results in a 3 minute (or other pre-set time) delay on initial activation. This delay allows time for personnel to leave the area before spraying starts after molds are brought in for cooling. The "delay" function could also be performed by a time delay relay, but such a relay is unnecessary if the "off" period of the timer is utilized for the delay. A normally-closed contact in the spray relay 60 opens during the spraying period to de-energize the recorder-controller 40 balance motor, so as to avoid erratic recording that may be caused by the spraying water. During this time, the recorder chart will

indicate a straight line at the interrupted temperature. The switching action of the spray timer 50 enables intermittent spraying during cooling of the molds to the desired temperature. As discussed above, intermittent cooling is desirable to minimize thermal stresses within the molds caused by drastic temperature reduction and the time intervals between spraying periods allow temperature differences within the mold walls to equalize.

The spray timer cycles the coolant spray on and off until the mold temperature drops below about 550% F., at which point low temperature contact 42 opens and de-energizes the spray timer 50. At about this point (525-550° F.) a low temperature range, normally open contact 46 in the recorder-controller closes and energizes a low temperature range-switching relay in the amplifier unit 30 to permit low temperature measuring and recording. A suitable spray relay is magnetic relay No. 5SRG made by Clark Controller Co. and described in Bul. No. 7305-PMS. A suitable spray solenoid is a 4-way solenoid valve ASCO No. 83441 made by the Automatic Switch Co. A suitable double-acting main water valve 72 is a 6-inch Dezurik Hydraulic Cylinder Operated Eccentric Valve, FIG. 128F made by Dezurik Corp., Sartell, Minnesota.

When molds are placed in the cooling station, the temperature is measured by the infrared sensing unit 20 which transmits a signal to amplifier 30. The amplifier regulates and amplifies the signal to provide an output to recorder 40 which is proportional to mold temperature. If the temperature is within the prescribed limits, e.g. 550° F. to 1100° F., as determined by the hi-low temperature contact settings 44 and 42 on the recorder-controller 40, the repeat cycle timer 50 is activated. The timer energizes (and de-energizes) the spray relay 60 in accord with pre-set time intervals and will continue to operate as long as it is energized by the recorder-controller, thereby providing the desired water-on (spray-on) and water-off (spray-off) cycles. The spray relay controls the opening and closing of the main water valve by activation of the corresponding pilot valve solenoid 70. The sensing unit 20 measures temperature continuously, whether the station is occupied or not, with the exception that the signal from it is blocked out during the water-on periods to avoid possible error introduced by the heavy blanket of water and steam.

Modifications may easily be made to increase or decrease the amount of control or read-out desired. Examples are (1) two-point controller rather than recorder-controller if recordings are not needed, (2) proportioning controller for more sensitive programming of spray action, (3) standby manual controls for experimental use or to insure operation in event of failure of automatic system, (4) thermostatic control of temperature of sensor head and/or amplifier environment using water or air for cooling and electricity for heating, (5) automatic drain valve to allow above ground piping to drain at end of cooling sequence during cold weather operation, (6) single-range recorder-controller rather than dual range if temperatures below 500° F. are not needed, or if auditing of time that molds are placed in or removed from the cooling station is not desired (7) multiple installation of sensing units (8) multiple installation of control system for independent zone or area control, (9) scanning equipment for mounting sensing head, (10) closed-circuit TV, mechanical, magnetic, or electronic limit switches, or other sensing devices for positioning buggies carrying molds in the cooling station.

It is apparent from the above that various changes and modifications may be made without departing from the invention. Accordingly, the invention should be limited only by the appended claims.

I claim:

1. An accelerated cooling apparatus suitable for cooling hot molds from which ingots have been removed comprising a narrow band infrared sensing means for sensing 15 radiant energy emission in the wave length range of 1

to 7 microns from a plurality of hot molds and to give an indication of the temperature relative thereto, a cooling system for spraying liquid coolant on said hot molds responsive to said sensing means such that below a maximum sensed radiant energy level and corresponding temperature range the coolant system is activated and below a minimum sensed radiant energy level and corresponding temperature range the coolant system is deactivated.

2. An apparatus in accordance with claim 1 for cooling hot iron molds, having means responsive to said sensing means to activate and deactivate said mold cooling system when the temperature corresponding to the sensed radiant energy emission of said molds is about 1100° F. and 500° F. respectively.

3. An apparatus according to claim 1 wherein said infrared sensing means senses and measures radiant energy within wave lengths of from 2.0 to 2.6 microns.

4. An apparatus according to claim 1 including a timer connected with the coolant system to apply coolant to the

hot molds intermittently while the coolant system is activated.
